GUARDRAIL ARRANGEMENT AND METHOD OF INSTALLING

BACKGROUND OF THE INVENTION

The present invention relates to a guardrail arrangement and a method of installing the same and is particularly concerned with guardrail arrangements adapted for use in connection with new buildings being constructed to guard floor openings and the edges of floors.

In the construction of buildings, it is usually the case that floors are put in place, as by forming the floors of cement poured into suitable forming, and this is done before walls are erected at the periphery of the floor and before other structure is installed which encloses the floor openings.

Further, tools and the like can easily fall off a floor at the edge of an opening, and this can represent a hazard to other personnel at a lower level.

Having the foregoing in mind, a particular object of the present invention is the provision of a guardrail arrangement for protecting the edges of a floor in a building under construction which is relatively inexpensive and which can readily be installed at the floor edge to be protected and readily removed therefrom.

Another object of the present invention is the provision of a method of erecting a guardrail of the above described nature in which little time is lost and wherein substantially all parts of the guardrail structure are reusable after being removed from a place of use.

BRIEF SUMMARY OF THE INVENTION

According to the present invention, when a floor is formed in a building under construction, connecting elements are fixed therein at the edges of the floor to be guarded. Such edges might be the outer periphery of the floor or might be in the form of elevator or stair well openings or the like formed in the floor.

After the floor is completely formed, and which may be accomplished by pouring concrete in suitable forms, the aforementioned elements become rigidly fixed in place and are adapted for detachably receiving guard posts in supporting relation thereto and which guard posts upstand vertically at the edges to be guarded. The posts are provided with straplike brackets through which rails can be inserted so as to form a guard fence which will completely guard the edge which is to be guarded.

The foregoing objects as well as still other objects and advantages of the present invention will become more apparent upon reference to the following specification taken in connection with the accompanying drawings in which:

FIG. 1 is a somewhat schematic perspective view showing a portion of a building floor at an edge thereof and showing a portion of a guardrail according to the present invention erected thereon;

FIG. 2 is a detail view of the post of the guardrail structure prior to being put in place so as to be fixed to the edge of the floor when the floor is formed;

FIG. 3 is a sectional view showing a typical post forming a part of the guardrail;

FIG. 4 is a section view indicated by line 4-4 on FIG. 2;

FIG. 5 is a section view taken on line 5-5 of FIG. 1;

FIG. 6 is a top view of the post looking in the direction of the arrows 6-6 of FIG. 2; and,

FIG. 7 is a section view taken on line 7-7 of FIG. 1.

DETAILED DESCRIPTION OF THE INVENTION

Referring to the drawings somewhat more in detail, in FIG. 1, 10 is the floor of a building which is under construction and which has been formed as by pouring concrete in concrete forms in a conventional manner.

FIG. 3 shows the floor 10 in edge view and illustrates a portion of the form in which the floor is poured. According to the present invention, dovetail members 14 (FIG. 5) are secured to the side of a form (not shown) as by nails and thus become firmly secured to the floor and remain in place in the floor at the edge thereof when the form member 12 is removed.

As will be seen in FIG. 1, the dovetail members 14 are distributed along the edges of the floor and provide slots 15 which open vertically upwardly and in a direction facing away from the edge to be protected while being closed at the bottom 17.

Each of the dovetail members 14 forms a floor mounted connecting element adapted for receiving a cooperating connecting element on a respective guard post 16. The connecting elements 19 which are welded at 21 on the guard posts 16 are inserted endwise into the dovetail members from the top and the posts 16 are thereby supported in substantially upright vertical position relatively to the floor 10 at the edges of the floor 10.

A typical post 16 is illustrated in FIG. 2 wherein it will be seen to comprise a length of pipe, say, 1½ inch standard pipe and which may be about 4 feet 4 inches or so in length. At the lower end of the pipe is the element 19 secured in place as by welding at 21 and comprising, for example, about an 8 inch length of round rod having a diameter of about thirteen-sixteenths of an inch. This length of rod forms the connecting element on the post 16 and is that element which slides endways into a slot in a respective dovetail member 14.

Distributed axially along the posts are straplike bracket members with the bracket member 20 at the upper end of the post being of a size to receive a standard 2 by 4. The bracket may be formed of strap material which is about one inch wide and one-fourth inch thick and is welded in place. About one foot below strap 20 is another bracket 22 formed of the same size material and of a size to receive, for example, a 1 by 6 piece of lumber.

About a foot below bracket 22 is a further bracket 24 the same size as bracket 22 and so located that the 1 by 6 rail supported therein will be adjacent the upper surface of the floor.

In FIG. 1, the 2 by 4 upper rail is indicated at 26, the 1 by 6 center rail is indicated at 28 and the 1 by 6 lower rail is indicated at 30.

These rails may be held against axial movement in the supporting brackets as by nails 31 which may be driven through the apertures 32 pierced in the bracket.

While the round bar 19 forms a suitable element for engaging the slot in the respective dovetail member, the pipe 16 may, if desired, have a connecting element fixed thereto to secure the bar in place and which substantially conforms in shape to the configuration of the slot in the dovetail member.

By the arrangement of the present invention, the guarding of the edges of a floor of a building under construction can quite easily be accomplished merely by placing the dovetail members 14 on the inside of the

forms in which the concrete making up the floor is poured. The members 14 are arranged in suitable distributed relation along the edges to be guarded and which, as mentioned, may be the outer edge of the floor or edges around openings for elevator shafts or stair wells.

While the guardrail is in place, the edges are adequately guarded, including the guarding of the region immediately above the floor and through which tools or other articles might accidentally fall.

It will also be apparent that the posts and the rails can easily be detached from the dovetail members for further use when the guardrail is no longer needed in a particular location.

The particular dimensions given above are not to be considered limiting in any respect. To conform with certain code requirements, the railing must be 42 inches high and have supporting posts spaced at not more than 8 feet on center, and the code, furthermore, requires the kick plate or kick rail at the base of the posts as has been described above. The invention, however, is not limited to the particular dimensions given above or employed in the specification but can vary widely depending on various circumstances.

Modifications may be made within the scope of the appended claims.

What is claimed is:

1. A safety guardrail, especially for use in buildings under construction to guard openings in the floor, comprising post means adapted to be supported substantially vertically adjacent the edge of the opening to be guarded, spaced bracket means on said post means adapted to receive and support horizontal rails therein, and cooperating elements of connecting means one disposed in the floor and the other forming a part of post means respectively and comprising a dove tail socket formed within the floor and forming a part thereof the floor adjacent said edge and a coacting means secured to one side of said post means and proportioned to be received in a vertical sense within said socket by upward and downward vertical movements and proportioned to prevent bending in any vertical plane out of such dove tail socket which reduces in dimension toward the outer edge of the floor to maintain said post means in a substantially vertical position adjacent said edge while providing for vertical insertion and removal

relatively to said dove tail socket.

2. A safety guardrail according to claim 1 in which said post means comprise a plurality of posts in spaced relation, each post having bracket means thereon to receive and support said rails, and each post and the floor adjacent the edge to be guarded having said cooperating elements thereon.

3. A safety guardrail according to claim 1 in which said cooperating elements comprise vertical slot means in one of said floor adjacent said edge and the lower part of said post means and bar-like means on the other thereof receivable endwise in said slot means.

4. A safety guardrail according to claim 2 in which said cooperating elements comprise a slot in the said edge to be guarded for each said post and open at the upper end and closed at the lower end, and a bar-like member fixed to the lower region of each post in parallel adjacent relation thereto and receivable endwise in the respective slot from above.

5. A safety guardrail according to claim 4 in which each said slot is open on the side facing away from the said edge and widens in a direction away from the open side thereof, each said bar-like member being wider in the lateral direction than the open side of said slot.

6. A safety guardrail according to claim 4 in which each said slot is open on the side facing away from the said edge and tapers outward in a direction away from the open side thereof, said bar-like member being round in cross section and larger in diameter than the open side of said slot.

7. A safety guardrail according to claim 4 in which each said slot is open on the side facing away from the said edge and tapers outward in a direction away from the open side thereof, said bar-like member being shaped to conform to the cross sectional shape of said slot.

8. A safety guardrail according to claim 1 in which said bracket means comprise straps formed to an angular configuration and fixed to said post means in axially spaced relation and forming with said post means rectangular spaces to receive said rails.

9. A safety guardrail according to claim 8 in which each angular strap is pierced to receive a fastener element to engage the respective rail to hold the rail against endwise movement in the respective strap.
